UNITED STATES PATENT OFFICE.

JOHN J. McTAVISH, JR., OF DETROIT, MICHIGAN.

ROTARY GAS-ENGINE.

1,124,494.

Specification of Letters Patent.

Patented Jan. 12, 1915.

Application filed December 5, 1912. Serial No. 735,069.

To all whom it may concern:

Be it known that I, JOHN J. McTAVISH, Jr., a citizen of the United States, residing at Detroit, county of Wayne, State of Michigan, have invented a certain new and useful Improvement in Rotary Gas-Engines, and declare the following to be a full, clear, and exact description of the same, such as will enable others skilled in the art to which it pertains to make and use the same, reference being had to the accompanying drawings, which form a part of this specification.

This invention relates to rotary gas engines of the four cycle type in which the explosive mixture is introduced between the ends of opposing pistons in a single cylinder. The cranks at opposite ends of the cylinder are each provided with a gear meshing with a stationary gear whereby the cylinder is made to rotate and a shaft is secured to the cylinder whose axis is coincident with the axis of rotation of the cylinder.

A further object of the invention is to eliminate the usual cams and rods for operating the inlet and exhaust valves which is accomplished by utilizing a rotating valve in communication with the interior of the cylinder between the two pistons therein, and the relation of the gears is such that two complete cycles of operation of the engine are produced during a single revolution of the cylinder. By such arrangement a multiplicity of parts is avoided and the combined momentum and power of the rotating pistons and cylinder is transmitted to the shaft from which it may be utilized in any well known manner.

These and further objects and novelties of the invention are hereinafter more fully described and claimed and shown in the accompanying drawings in which—

Figure 1 is a vertical section of an engine embodying my invention. Fig. 2 is a side elevation partly in section showing the rotating valve and ports controlled thereby and a portion of the stationary gear with which the gears on the crank shaft mesh. Fig. 3 is a side elevation showing the casting in section and a diagram of the electric circuit by means of which the explosive charge may be ignited. Fig. 4 is a detail of the contact pin through or by means of which current may flow to the spark plug. Fig. 5 is an elevation of the commutator

plate. Fig. 6 is an enlarged cross-section of the rotary valve. Fig. 7 is a detail showing the shape of the port in the valve. Fig. 8 is a detail of an alternative form of the device.

Similar characters refer to similar parts throughout the drawings and specification.

The engine consists primarily of a stationary casing 1 provided with a bearing for the shaft 2 to which is secured the cylinder 3. The cylinder is preferably provided with a lining 4 and the shaft terminates at the lining as shown in Fig. 1. Like pistons 5 are mounted in each end of the cylinder connected by the usual connecting rods to a crank shaft 6 mounted in crank cases 7 secured to opposite ends of the cylinder. Each of the crank shafts is provided with a spur gear 8 meshing with a stationary gear 9 secured to the casing whose center is coincident with the shaft center and the rotation of the crank shafts by reason of the reciprocation of the piston produces a rotation of the cylinder and pistons due to the travel of the gears 8 about the master-gear 9. In this connection it is to be noted that the crank shafts should be slightly offset in their relation to the pistons in the direction of rotation of the cylinder in order that an explosion between the two pistons cannot take place on the "dead center" and therefore each gear 8 will rotate in the same direction and produce the desired rotating movement of the cylinder. The cylinder is provided with an aperture 10 leading into the explosion chamber in the cylinder between the ends of the pistons therein located directly opposite the shaft 2 and in line therewith and mounted on the cylinder in axial alinement with the shaft is a cylindrical rotary valve 11 provided with a passageway leading to the port 10 in the cylinder. The valve is seated in a chamber provided therefor in the casing and serves as a support for the cylinder in addition to the support provided by the shaft 2. As shown more fully in Fig. 2, there are two intake ports 12 and 13 and two exhaust ports 14 and 15 provided with passages leading into the valve chamber and the two intake ports and the two exhaust ports may be connected by a manifold to a single intake and single exhaust lines respectively, the exhaust manifold being indicated by dotted lines in Fig. 1. The valve 11 is provided

with a port 16 leading to the central passageway and this port 16 in the valve successively registers with each of the intake and exhaust ports during a single 5 revolution thereof and the operation is as follows:—When the port 16 is in registration with the intake port 12, the pistons are traveling outward in the cylinder thereby drawing a charge thereinto. 10 As the port 16 continues its movement the charge in the cylinder is compressed and ignited and the relation of the gears 8 to the master-gear 9 is such that this cycle of operations is completed when the port 16 15 registers with the exhaust port 14 and the cylinder exhausted of burnt gases and as the valve continues its movement and comes into registration with the intake port 13 the pistons are again on the intake stroke 20 and the cycle of operations again completed at the time the port is in registration with the exhaust port 15 and these two explosions occur during each revolution of the cylinder. The charge in the cylinder is ignited 25 by means of a spark plug 20 positioned midway between the pistons therein as shown in Fig. 1 and current may be supplied to the spark plug in any manner usual with gas engines, one method of which is shown diagrammatically in Fig. 3 in which 30 one terminal of a spark coil is connected to both contact plates 21 and 22 mounted on a commutator disk 23 which is loosely mounted on a cylindrical hub 24 on the cylinder. To the disk is secured a pin 25 to which is secured in any convenient manner an operating rod 26 whereby the disk 23 may be positioned in a manner to advance or retard the time of explosion. Mounted 35 on the cylinder and insulated therefrom, as shown more clearly in Fig. 4, is a spring pressed contact pin carried in the block 27 secured to the insulating plate 28 and this pin is continuously in contact with the disk 23 and during the revolution of the cylinder contacts the plates 21 and 22 at the proper 40 intervals to ignite the compressed charge. 45 In order that no loss of compression may take place through the port 16 and the interstice between the valve 11 and the chamber in which it is mounted, the valve is provided with a circumferential groove 30 about the port 16 and a packing ring 31 inserted therein and this ring 31 is held in 50 contact with the wall of the chamber by means of the coil springs 32 as shown in Fig. 6, and a leakage through the port thereby prevented. The port, as shown in Fig. 55 7, is longer in the direction of its travel than 60 transverse thereto, and by this arrangement the intake and exhaust ports which are substantially of a diameter equal to the width of the valve port, are practically fully opened as the forward edge of the port in 65 the valve passes the edge of the intake port

and prevents what is termed "wire drawing" at the time of opening and closing of either of the ports.

The casing is preferably formed in halves secured together and that part of the casing 70 in which the shaft is mounted is provided with a base for the support of the casing and that half of the casing in which the rotary valve is mounted may be detached from the other part of the casing whereby 75 the valve and other portions of the mechanism are accessible for inspection or repair.

While I have described the crank as having but a single gear thereon meshing with a stationary gear on the casing, the cranks 80 may be formed as shown in Fig. 8 with a gear upon each end thereof meshing with stationary gears correspondingly positioned upon opposite sides of the casing, such alternative form of the structure being of 85 greater strength and the cranks are also relieved of excessive side strain.

While I have shown a simple method of electric ignition it is to be understood that any well known method or device may be 90 used for this purpose without departing from the spirit of this invention.

Having thus described my invention and its method of operation, what I claim and desire to secure by Letters Patent of the 95 United States is—

1. In an internal combustion engine, a cylinder mounted for rotation about an axis, pistons in said cylinder in opposed relation and arranged for simultaneous actuation by 100 an exploded charge, a crank shaft for each piston mounted at the opposite ends of the cylinder, a gear on each crank shaft, a stationary gear mounted concentric with the axis of rotation of the cylinder with which 105 said crank gears mesh, a port in said cylinder whose center is coincident with the axis of rotation, a valve cylindrical in form secured to the cylinder provided with a passageway leading to the port therein, a valve 110 chamber in which said valve is mounted for rotation with the cylinder, said valve having a port in the circumference thereof in communication with the said passageway, and inlet and exhaust ports in the wall of the 115 chamber with which the port in the valve successively registers during the rotation thereof.

2. In an internal combustion engine, a casing, a shaft mounted in bearings in the casing, a cylinder secured to the shaft whose 120 center coincides with the axis of rotation of the cylinder, a pair of pistons in said cylinder in opposed relation and arranged for simultaneous actuation by an exploded charge, a crank shaft for each piston mounted at opposite ends of the cylinder, a gear on each crank shaft, a stationary gear mounted on the casing concentric with the shaft with which the crank gears mesh, a port in 125 said cylinder whose center is coincident with 130

the axis of rotation, a cylindrical valve secured to the cylinder in alinement with the shaft having a passageway in communication with said port, a valve chamber in said casing forming a bearing for the valve, said valve having a port in the wall thereof, a packing ring surrounding the port, and intake and exhaust ports in the valve chamber with which the valve port successively registers during its rotation.

3. In an internal combustion engine, a cylinder mounted for rotation about an axis, a pair of pistons in said cylinder in opposed relation and arranged for simultaneous actuation by an exploded charge, a crank shaft for each piston mounted at opposite ends of the cylinder, a gear on each crank shaft, a stationary gear concentric with the axis of rotation of the cylinder with which the crank gears mesh, a port in the cylinder between the pistons through which the cylinder receives the explosive charge and exhausts the products of combustion, a cylindrical valve having a passageway communicating with said port, said valve being mounted on the cylinder concentric to the axis of rotation thereof, a valve chamber in which the valve is seated, and a plurality of intake and exhaust ports in the wall of said chamber with which the valve successively registers in timed relation with the operation of the pistons.

4. In an internal combustion engine, a

casing, a shaft mounted in a bearing in the casing, a cylinder secured to the shaft the axis of which is coincident with the axis of rotation of the cylinder, a pair of pistons in said cylinder in opposed relation and arranged for simultaneous actuation by an exploded charge, a crank shaft for each piston mounted at opposite ends of the cylinder, a gear on each end of each crank shaft, stationary gears mounted on opposite sides of the casing, the center of which is coincident with the axis of rotation of the cylinder and with which the gears on the crank shaft mesh, said cylinder having a port between the pistons therein through which it may receive an explosive charge and exhaust the products of combustion, a cylindrical valve secured to the cylinder in alinement with said shaft having a passageway in communication with said port, a valve chamber in said casing forming a bearing for the valve, said valve having a port in the wall thereof, and intake and exhaust ports in the wall of the valve chamber with which the valve port successively registers during the rotation of the valve.

In testimony whereof, I, sign this specification in the presence of two witnesses.

JOHN J. McTAVISH, JR.
